US00D784404S

(12) **United States Design Patent** (10) **Patent No.:** **US D784,404 S**
(45) **Date of Patent:** **** Apr. 18, 2017**

(54) **DISPLAY SCREEN PORTION WITH ICON**

(71) Applicant: **Sonos, Inc.**, Santa Barbara, CA (US)

(72) Inventors: **Liesbeth van den Berg**, Medford, MA (US); **Abhishek Kumar**, Santa Barbara, CA (US)

(73) Assignee: **Sonos, Inc.**, Santa Barbara, CA (US)

(**) Term: **14 Years**

(21) Appl. No.: **29/484,347**

(22) Filed: **Mar. 7, 2014**

CLAIM

The ornamental design for display screen portion with icon, as shown and described.

DESCRIPTION

The sole FIGURE is a front view of a display screen portion with icon showing our new design.

The broken lines illustrate the boundaries of a display screen portion and forms no part of the claimed design.
